CONTAINER

Charles K. Dunlap, Hartsville, S. C., assignor to
 Sonoco Products Company, Hartsville, S. C., a
 corporation of South Carolina

Application June 14, 1938, Serial No. 213,660

3 Claims. (Cl. 229—4.5)

This invention relates to containers and particularly to containers of all-paper construction and primarily intended for use in the dispensing of liquids.

5 A paper container which is intended for use in the packaging and dispensing of liquids must of necessity be self-supporting, i. e., must maintain its shape at all times despite the unstable nature and outward pressures exerted against its inner 10 surfaces at various points by the container liquid, and despite the shocks and abrasions due to rough handling in transportation or at the point of consumption of the liquid commodity. Naturally paper containers for such commodities as oil 15 meet with widely varying conditions between the times when they are charged and sealed and the times when they are opened and the contents discharged, some containers travelling short distances and not being subjected to any appreciable rough handling and other containers being transported longer distances to various points of consumption, on trucks or railroads and are, enroute, considerably buffeted.

20 A paper container which is fabricated in such manner that it is well able to withstand all shock incident to handling and transportation without substantial injury must naturally be much more staunchly constructed than one which will not be subsequently subjected, after charging, to rough handling. Also a heavily built paper container is more costly to fabricate than one of light construction and hence the total cost of distributing a liquid commodity will be greatly increased if all the containers in which such commodity is packaged are constructed to successfully withstand the most severe blows and shocks to which any one of them may conceivably be subjected.

25 In accordance with the present invention a paper container is provided, which comprises essentially, in addition to the container proper, a reinforcing envelope which is separately formed and applied and which may or may not be used at the option of the container manufacturer, 30 having in mind the ultimate destination of the container and the nature of transportation and handling shocks to which it will be subjected enroute to such destination. The two-part container provided by the invention promotes economy in use of such containers for the dispensing of liquids since, while a container of maximum strength and somewhat increased cost, may be supplied where necessary, the strength and cost of the container may be reduced where the extra strength is actually not necessary.

The invention pertains particularly to containers of the conical type the most vulnerable portion of which, when charged, is the main member or conical wall or body of the container. The container proper is frusto-conical, having 5 flat parallel top and bottom closures and the conical body or wall is fabricated of sheet paper, rolled on a mandrel. Where it is expected that the container, after being charged, will be subjected to rough usage, a frusto-conical envelope 10 is slipped over the container body proper and secured in such position, the protective envelope likewise comprising a sheet of paper rolled into conical form on a mandrel. This envelope, 15 when used, is secured in position by means of an adhesive and is exteriorly decorated with designs or legends in the same manner that the body of the container proper is normally decorated.

20 By the use of the novel protecting envelope the top and bottom closures of the conical container may likewise be strengthened and the invention contemplates also the fabrication of a container of conical type in which the top and bottom closures are so applied to the body thereof that the outer wall or protective envelope 25 engages portions of these closures and more firmly secures them in position.

25 The invention likewise contemplates certain improvements in the details of construction of the top and bottom closures, quite regardless of 30 whether or not the protective envelope is employed. Preferred embodiments of the invention are disclosed in the accompanying drawings by way of example, in which:

35 Figure 1 is a perspective view of the container proper, without the protective envelope or outer wall, portions being broken away to show the interior construction of the container and to disclose the means for sealing its ends;

Figure 2 is a perspective view of the container 40 outer wall or protective envelope;

Figure 3 is an axial section through the completed container with envelope assembled therewith;

Figure 4 is an axial section through a modified 45 type of container to which has been applied a protective envelope;

Figure 5 shows in section the upper end of the same container and the two closure caps, the several parts being spaced apart; and 50

Figure 6 is an axial section through a further and very simple type of container with which the protective envelope may be used if desired.

In the fabrication of the container proper, which is shown in Figure 1, a sheet of paper is

- wound into conical form upon a conical mandrel, the blank prior to the winding operation being coated with a suitable adhesive so that the several convolutions of the paper are rigidly secured thereby into a rigid structure. After winding, the tip and base of the conical member are accurately trimmed so that the resulting container body, indicated at 10, is truly frusto-conical, its upper and lower edges lying in parallel planes.
- 5 10 Its outer surface may be decorated with legends and ornamental figures to indicate the nature of its contents, and the manufacturer thereof. Its bottom closure comprises two flanged discs, an inner disc 11 and outer disc 12, the flange 11' 15 of the inner disc being itself frusto-conical so as to closely engage the inner surface of the frusto-conical body 10. The flange 12' of the outer disc is also frusto-conical, or at least is made so by a rolling operation after assembly 20 of the disc 12 and body 10, in order that the inner surface of this flange will closely engage the outer surface of the body 10. Suitable adhesive substances are employed to secure the discs in the positions in which they are shown and all surfaces 25 of the closure discs, as well as the inner surface, and preferably also the outer surface, of the body 10 are coated with a substance which will prevent penetration of the liquid contents of the container, after it is charged, into the fibrous walls of the container. The container is charged after assembly of the bottom closure but prior to closure of the small end, in which event the top closure will comprise a disc 13, having a peripheral frusto-conical flange 13' which engages the outer surface of the body 10 at its upper end. In the event that the container is charged through its bottom or larger end, the closure means for the small end may comprise, in addition to the flanged disc 13, an inner flanged disc 14, the 30 peripheral frusto-conical flange 14' of which closely engages the conical inner surface of the body 10 at its upper end. Suitable adhesive substances are employed to secure the closure discs 13 and 14 in the positions in which they are shown.
- A container formed as just described is sufficiently durable to withstand all shocks and blows due to ordinary handling and transportation. Where the container is to be transported long 35 distances, however, or it is expected that, due to any one of various reasons, it will or may be subjected to rougher handling, a frusto-conical reinforcing envelope may be placed over it. Such an envelope is illustrated in Figure 2 and will be seen to comprise a conical member 15, open at top and bottom. It is also formed by winding an adhesive coated paper sheet upon a conical mandrel and thereafter accurately trimming the ends of the resulting article. Prior to assembly with the container proper its exterior surface 40 may be appropriately decorated and its inner surface coated wholly or partially with an adhesive. When assembled the inside surfaces thereof adjacent its upper and lower ends will bear 45 against and closely engage the exterior surfaces of the flanges 12' and 13' of the outer, lower and upper closure discs 12 and 13. After the adhesive has dried the envelope 15 is firmly secured in position and not only serves as a protector for 50 the conical wall of the container proper but likewise as an auxiliary means for securing the closure discs 12 and 13 in position. Hence not only is the side wall of the container strengthened but likewise its top and bottom seals. As 55 has previously been pointed out, the envelope 15

is made use of only when necessary and hence a very substantial saving is realized in the production and wide distribution of a large volume of a liquid commodity such as oil, the wall of the container proper 10 being made only just sufficiently thick and durable to withstand minor shocks incident to local transportation and handling.

The protective envelope may be permanently attached to the container proper, if desired, by 10 inturning its edges so as to engage the top and bottom seals of the container. Such a construction is shown in Figure 4, where the envelope 20 has its inturned edges 20' and 20² in engagement with the top and bottom sealing caps 21 and 22 15 respectively. It will be observed that, in this form of container, both of the sealing caps 21 and 24 may be applied from the outside, so that the container may be charged with liquid introduced through its small end or top opening. It 20 will be perceived that the outer sealing cap 21 has a frusto-conical flange which fits against the outer surface of the container body 23 whereas the cup-shaped inner sealing cap 24 has a peripheral flange 24' which is adapted to rest 25 upon the upper edge of the container body 23. Both caps are retained in position by an adhesive coating substance and by the inturned edge of the outer envelope. It will be observed that the liquid contents of the container cannot come into contact with the edge of either of the caps 21, 24 or with the edges of either of bottom closures 22 or 25, which is an advantageous construction because liquid will more easily penetrate paper if brought into contact with an edge than if it contacts with a side surface. All surfaces of the container which are to contact with liquids are of course coated with a leak-proofing coating composition and the top and bottom closure discs are preferably coated on all surfaces by dipping, prior to assembly.

In the form of container shown in Figure 6 the top is closed by a single cap 30 and the bottom by a single flanged disc 31. The flange 31' of disc 31 is cylindrical when the disc is applied to the container body 32, as indicated in dotted lines, but is inwardly deflected by a rolling operation to its full line or container wall engaging position.

Having thus described the invention, what is claimed as new and desired to be secured by Letters Patent is:

1. A self-supporting conical paper container comprising a hollow frusto-conical body portion and closures for the ends thereof, each such closure comprising a disc having a peripheral frusto-conical flange, the inner surface of each flange closely engaging the outer surface of said body portion, and a separately formed relatively stiff frusto-conical paper envelope enveloping the said body portion and closely engaging and securing said flanges.
2. A self-supporting conical paper container comprising a hollow frusto-conical body portion, closures for the ends thereof, the closure for the larger end being a disc which bridges said opening and bears against the annular end surface of the body, said disc having a frusto-conical peripheral flange the inner surface of which closely engages the outer surface of the body and is secured thereto by an adhesive, and a relatively stiff frusto-conical paper outer envelope for said body, the inner surface of said envelope at the larger end thereof closely engaging and

securing the peripheral flange of said closure disc.

3. A self-supporting conical paper container comprising a hollow frusto-conical body portion and closures for the ends thereof, each end closure including two closure discs disposed transversely of the body, both discs at each end having integral peripheral frusto-conical flanges,

the flange of one disc closely engaging the inner surface of the body and the flange of the second disc closely engaging the outer surface of the body, and a relatively stiff, frusto-conical envelope encircling said body and closely engaging the flange of said second disc. 5
